DESIGN FOR A TEXTILE FABRIC

Samuel Salsky, New York, N. Y.

Application October 16, 1945, Serial No. 122,874

Term of patent 3½ years

(Cl. D92—1)

To all whom it may concern:

Be it known that I, Samuel Salsky, a citizen of the United States of America, residing in New York city, county of New York, and State of New York, have invented a new, original, and ornamental Design for a Textile Fabric, of which the following is a specification, reference being had to the accompanying drawing, forming part thereof.

The figure on the drawing is a plan view of a

textile fabric showing my new design, a design unit of which is outlined by broken lines. The repetition of the design unit is indicated by the corresponding parts, A and A', of two adjacent units.

I claim:

The ornamental design for a textile fabric, substantially as shown and described.

SAMUEL SALSKY.
